IGNITION MECHANISM FOR INTERNAL-COMBUSTION ENGINES.

1,204,104.

Specification of Letters Patent.

Patented Nov. 7, 1916.

Application filed January 14, 1916. Serial No. 72,028.

To all whom it may concern:

Be it known that we, ERNEST C. WILCOX and JOHN F. CAVANAGH, citizens of the United States of America, both residing at 5 Meriden, Connecticut, have invented a new and useful Ignition Mechanism for Internal-Combustion Engines, of which the following is a specification.

This invention relates to improvements in 10 ignition apparatus for internal combustion engines, and particularly to the means for controlling the timing of the spark and the mounting and assembling of the various parts of the timing and distributing mechanism.

15 The object of this invention is to simplify and improve the construction of such parts whereby they may be manufactured at relatively small cost without sacrifice to quality and whereby the apparatus may be easily 20 assembled and adjusted and disassembled, and whereby renewals may be quickly and cheaply effected.

For example, the timer element in an apparatus of this character is one part that 25 is subject to the greatest wear and requires after a time readjustment or replacement. It is our plan to so construct this part of the apparatus that it can be made so cheaply and can be so easily replaced that an entirely new part fully assembled may be purchased at trifling cost and substituted in 30 place of the old one, without requiring any special skill.

Again, our new construction provides a 35 novel method of mounting and adjusting, and whereas in constructions heretofore provided the entire timer and distributor head has been made axially adjustable for the purpose of varying the moment of the 40 spark. In this case the entire timer head is rigidly mounted, the only moving parts being inclosed and protected. This is of advantage because it saves wear on the mechanical parts and upon the various electrical 45 connections.

These and other advantages will be apparent to the mechanic skilled in the art from a reading of the following description and by reference to the accompanying 50 drawings, in which—

Figure 1 is a side elevation partly in section. Fig. 2 is a longitudinal sectional view thereof on the plane of the line 2—2, Fig. 1. Fig. 3 is a plan view with the top

removed. Fig. 4 is a perspective view of 55 several parts arranged one above the other in the order in which they are applied. Fig. 5 is a section of certain parts on the plane of the line 5—5, Fig. 3. Fig. 6 is a perspective view of a bushing diagrammatically illustrating an oil groove.

1 represents a supporting frame which carries the combined timer and distributor, which frame may be for example, an integral part of an engine casting with which 65 the timer and distributor is associated.

2 is a sleeve-like projection on the underside of the combined timer and distributor which fits into the frame 1.

3 is a lug on the side of the sleeve 2 which 70 projects between two adjusting screws 4—5 carried by the frame 1. By adjusting these screws 4—5, the relative angular adjustment of the sleeve 2 in the frame 1 may be easily effected. Mounted on the upper part of 75 the sleeve 2 is what we may term the timer housing 6. Mounted on this part 6 is what we may term the distributor housing 7. This part 7 is ordinarily made of some insulating material and fixed therein are the distributor terminals 8—8. In this instance the apparatus is designed for a four cylinder engine, and, therefore, has four distributor terminals arranged radially around the housing 7, and a single central terminal 9 85 in common to all of the terminals 8—8.

10 is a bushing which is preferably provided within the sleeve 2 to provide a suitable bearing for the timer shaft 11.

12 is a driving gear at the lower end of 90 the timer shaft 11. The upper end of the timer shaft 11 is provided, in this instance, with four cams 14—14 to operate the timer arm.

15 is the timer arm pivotally mounted 95 at 16 upon a carrier plate 17 which is mounted for partial rotation in the lower part of the timer housing 6. This timer arm 15 carries the usual contact point 18 at its free end which makes an intermittent 100 make and break contact with the timer point 19 which is by preference adjustably mounted upon a supporting plate 20 which is likewise mounted upon the carrier plate 17 but is insulated therefrom by the insulation 21.

22 is a low tension terminal wire electrically connected with the supporting plate

20 and hence with the point 19. In this instance the point 18 is grounded. Obviously as the shaft 11 is rotated, the cams will intermittently engage the timer arm 15 and move the point 18 away from the point 19. The usual anti-friction roller 23 may be provided to reduce friction, said roller being carried by the timer arm 15 in the path of the cams 14. A spring 24 serves to swing 10 the arm 15 in direction to bring the points 18-19 together. Removably fixed upon the upper end of the shaft 11, in this instance above the cams 14, is a radial distributor arm 25. This arm is usually made of insulating material and carries an electric contact element 26 which is in electrical connection at all times with the distributor terminal 9, for example, by means of a contact spring 27. The contact 26 preferably does 15 not actually engage the lower ends of the distributor terminals 8-8, but sweeps past the same successively and so close thereto that the high tension current which is distributed to the various spark plugs (not shown) may easily jump the gap. The carrier plate 17 for the timer piece or member may be held against improper displacement in any suitable way, for example, it may be centrally supported by a short hub 28 in the 20 bottom of the timer casing (see Fig. 4) and may be held on the bottom of the casing by a washer 29 which is in turn held in place by screws 30-30. Between the washer 29 and the top of the carrier plate 17 we may 25 also dispose, if desired, a spring washer 29^a of comparatively thin material, the presence of which washer serves to prevent any binding engagement between the rigid washer 29 and the top of the carrier plate. Projecting 30 downwardly from the carrier plate is a pin 31, said pin passing through a slot 32 in the bottom of the timer housing as best seen in Figs. 4 and 5.

33 is a lever pivotally mounted on the underside of the timer housing, for example, as indicated at 34. This lever has a slot in its end and engages the pin 31 so that by swinging the lever 33 the timer element may be bodily rotated in one direction or the other within the stationary housing so that the moment of separation of the spark points 18-19 may be varied to produce an "early" or "late" spark, as desired. Any suitable means, for example, spring clips 35-35^a 35 may be employed to connect the two parts 6 and 7.

36 represents an oil or a grease cup which is in communication with the interior of the bushing 10, whereby the shaft 11 may be 40 properly lubricated. The interior of said bushing may be provided with a suitable spiral groove or grooves as conventionally shown at 37, Fig. 6, and we prefer to provide a drain outlet 38 to drain off any excessive 45 amount of oil that may tend to creep up into

the timer. The bottom of the timer housing 6 also has a second slot 39 to afford clearance for the terminal wire 22.

Having now described the preferred form and arrangement of the various parts of our invention, we will now describe its operation. The apparatus is so mounted on an engine of the internal combustion type, that the gear 12 will properly mesh with a co-operating gear on the cam shaft (not shown) thereof, the proper mounting being one that will place the arm 25 at the top of the shaft 11, in approximately the proper position relatively to the distributor points with which it coacts. If it is impossible to effect precisely the proper adjustment by the meshing of the gears, any variation therefrom may be compensated or taken up by the adjusting screws 4 and 5. With the apparatus thus mounted, when the engine is running the timer element will be intermittently operated to make and break the connection between the points 18 and 19 for the purpose of determining the timing moment of the spark. This moment may be advanced or retarded by swinging the arm 33 in the proper direction. This swinging of said arm does not shift any exposed part, but as before stated, shifts the timer element angularly around the axis of the shaft 11 to the desired degree. Hence, the only place where wear occurs will be either in the timer element itself or in the bearing support therefor. In the event any portion of the timer element should be unduly worn or broken, it is merely necessary to remove the part 7, remove the screws 30-30 and the washers 29-29^a whereupon, by disconnecting the lower end of the wire 22, the entire timer element may be removed and discarded 95 and a new one substituted.

We have found that the entire timer element constructed as referred to may be so economically produced and sold that the cost of making this change or substitution is 100 so slight that it is far better to effect such substitution than to attempt to either repair or replace or substantially readjust any of the parts thereof. Furthermore, by the aforesaid construction, these changes may 105 be made by any one without the exercise of special skill and without the use of special tools.

What we claim is:—

1. In an igniter apparatus of the character described, a timer housing, a unitary timer stationary element mounted therein and bodily removable therefrom and thereon and comprising a carrier movable relatively to said housing, a contact arm mounted on 120 said carrier and having a contact point, a second stationary co-operating contact point mounted on said carrier and rotatable means for intermittently operating said arm to separate said contact points, with means 125

mounted independently of said timer element for moving said carrier to vary the moment of operation of said cam on said arm.

5 2. In an igniter mechanism, a stationary timer housing, a cam shaft projecting thereto and having a cam arranged therein, a timer element removably mounted in and on said housing and angularly adjustable therein relatively thereto and to said cam shaft, and means arranged externally of said timer housing and mounted independently of said timer element for shifting said timer element.

10 3. In an igniter mechanism, a relatively stationary timer housing, a relatively stationary distributor housing carried thereby and having distributor terminals, a cam shaft having a cam projecting into the timer 20 housing, a radial distributor arm carried by said cam shaft and projecting into said distributor housing, a timer element mounted within and on said timer housing and including a carrier having a passage of sufficient size to permit said cam to pass therethrough, a movable contact arm mounted thereon having a contact point, a relatively stationary contact point also mounted on said carrier, said interrupter element being 25 adjustable relatively to said stationary timer housing and distributor housing, and means mounted on the outside of said housing and projecting into the same for adjusting said interrupter element, and means for adjusting the stationary timer housing and distributor housing relatively to and around 30 the axis of said cam shaft.

4. In an igniter mechanism, a relatively stationary distributor part including at least 40 two terminals, a rotatable distributor arm including a contact adapted to intermittently close the circuit between said terminals and including a rotatable shaft, a timer housing surrounding said shaft and a timer element inclosed in said housing and mounted thereon, said timer element being rotatably adjustable relatively to said housing, said housing being relatively stationary, with means mounted independently 50 of said timer element and outside said housing for rotatably shifting said timer element, said timer element including two make and break contacts, one of which at least is insulated from said timer element 55 and said housing.

5. In an igniter mechanism, a relatively stationary timer and distributor housing with means for rotatably adjusting the same relatively to a fixed part, a shaft projecting 60 into said housing, a radial distributor arm carried by said shaft within said housing, a cam carried by said shaft within said housing, said two housings being separable, a partially rotatable timer element removably 65 mounted within and on said housing and in-

cluding a carrier, a contact point carried thereby and stationary relatively thereto and another coöperating contact point carried thereby and movable relatively thereto, and means for moving said last mentioned 70 contact point through the medium of said cam and means mounted independently of said timer element and external of said housing for moving said contact element in said housing to vary the moment of operation of said cam on said movable point.

6. In an igniter mechanism, a stationary housing, timer and distributor mechanism arranged within the housing, a cam shaft having a cam entering the housing and co-operating with said mechanism, said timer mechanism including a removable carrier having a passage of sufficient size to permit said carrier to be passed over said cam and mounted for partial rotation within the stationary housing, with means in said housing for centering said carrier, an operating member mounted externally of said housing and independent of said carrier, and means for detachably connecting said carrier with 90 said operating member, said timer mechanism being wholly mounted on said housing independently of said cam shaft.

7. In an igniter mechanism, a stationary housing, timer and distributor mechanism 95 arranged within the housing, a cam shaft entering the housing and co-operating therewith, said timer mechanism including a removable carrier mounted for partial rotation within the stationary housing, an operating member mounted externally of said housing, and means for detachably connecting said carrier with said operating member, comprising a pin carried by one of said parts, said housing having a clearance slot 105 for said pin and a recess in the other part for receiving said pin whereby movement of the operating member will shift the position of said carrier relatively to the said housing and cam shaft.

8. In an igniter mechanism, a stationary housing, timer and distributor mechanism arranged within the housing, a cam shaft entering the housing and co-operating therewith, said timer mechanism including a removable carrier mounted for partial rotation within and on the stationary housing, an operating member mounted independently of said carrier and externally of said housing, and means for detachably connecting said carrier with said operating member, 115 said timer mechanism mounted on said carrier comprising a pivoted arm carrying a contact point, and a stationary arm carrying another contact point, said stationary 120 arm being insulated from said carrier.

9. In an igniter mechanism, a stationary housing, timer and distributor mechanism arranged within the housing, a cam shaft entering the housing and co-operating there- 130

- with, said timer mechanism including a removable carrier mounted for partial rotation within and on the stationary housing, an operating member mounted externally of 5 said housing, and means for detachably connecting said carrier with said operating member, said timer mechanism mounted on said carrier comprising a pivoted arm carrying a contact point, and a stationary arm 10 carrying another contact point, said stationary arm being insulated from said carrier, a terminal wire electrically connected with said stationary arm and extending outside of said housing, said housing having a 15 clearance passage therefor of sufficient size to permit said terminal wire to be moved freely with said carrier as the latter is shifted in said housing.
10. In an igniter mechanism, a stationary 20 housing, a mounting therefor, a cam shaft arranged to project into said housing, means for angularly adjusting said housing relatively to the axis of the cam shaft to various fixed positions, timer and distributor mechanism within said housing, said distributor mechanism including a stationary distributor point, and a rotatable distributor point carried by said cam shaft, said timer mechanism including a removable carrier rotatably mounted within and on said housing and having one contact point stationary thereon but movable therewith relatively to said housing, and a second contact point 30 thereon movable with relation to both the carrier and the housing, with a cam on said shaft for moving said last contact in one 35 direction, and with means mounted independently of said carrier and outside of said housing for moving said carrier and its contact points angularly around the axis of 40 said cam shaft to vary the moment of operation of the cam on said last mentioned contact points.
11. In an ignition mechanism, a housing, a high tension current distributing means 45 therein, a low tension current interrupter therein, two terminal points for said distributor and two terminal points for said interrupter, one of said four points being fixed relatively to said housing, the others 50 being movable relatively thereto, and means external of said housing for moving the last mentioned interrupter points, said means being mounted independently of said interrupter. 55
12. In an igniter mechanism, a main support, a relatively stationary timer and distributor housing mounted thereon, an adjusting screw means between said support and housing for angularly adjusting said 60 parts, a timer element removably mounted within said housing and rotatably supported therein, a distributor element within the housing, a cam shaft entering the housing coöperating with the timer and distributor elements and means mounted independently of said timer element and external of the housing for shifting the timer element relatively to said housing. 65

ERNEST C. WILCOX.
JOHN F. CAVANAGH.
